US00D742251S

(12) **United States Design Patent**
Kaanta et al.

(10) **Patent No.:** **US D742,251 S**
(b4) **Date of Patent:** **** Nov. 3, 2015**

(54) **TWO-PIECE CONTOURED METALLIC CONTAINER**

(71) Applicant: **Ball Corporation**, Broomfield, CO (US)

(72) Inventors: **Jason M. Kaanta**, Pine, CO (US);
Daniel A. Edwards, Westminster, CO (US)

(73) Assignee: **Ball Corporation**, Broomfield, CO (US)

(**) Term: **14 Years**

(21) Appl. No.: **29/496,738**

(22) Filed: **Jul. 16, 2014**

(51) LOC (10) Cl. **09-01**

(52) U.S. Cl. **D9/772**

Primary Examiner — Keli L Hill

(74) Attorney, Agent, or Firm — Sheridan Ross P.C.

(57) **CLAIM**

The ornamental design for a two-piece contoured metallic container, as shown and described.

DESCRIPTION

FIG. 1 is a front perspective view of the two-piece contoured metallic container;

FIG. 2 is a front elevation view thereof;

FIG. 3 is a top plan view thereof; and,

FIG. 4 is a bottom plan view thereof.

The broken lines showing a two-piece contoured metallic container are included for the purpose of illustrating environment and form no part of the claimed design.

1 Claim, 2 Drawing Sheets
